UNITED STATES PATENT OFFICE.

JOHN DEMAREST, OF NEW YORK, N. Y., ASSIGNOR TO THE J. L. MOTT IRON WORKS, OF SAME PLACE.

WATER-CLOSET CISTERN.

SPECIFICATION forming part of Letters Patent No. 378,294, dated February 21, 1888.

Application filed October 17, 1887. Serial No. 252,546. (No model.)

To all whom it may concern:

Be it known that I, JOHN DEMAREST, of the city and State of New York, have invented an Improvement in Water-Closet Cisterns, of which the following is a specification.

Water-closets have been made in which there is a siphon in the discharge or sewer pipe, and this siphon is exhausted by the action of the water rushing out of the cistern.

10 My present improvement relates to the cistern made use of with this character of closet.

In the drawings, Figure 1 is a vertical section of my improved cistern. Fig. 2 is a sectional plan at the line *xx*, and Fig. 3 is a section of the valve in a modified form.

15 The cistern A is to be of any desired size, and the water is supplied by a pipe, B, and ball-valve, C, as usual, and there is a minus pressure-chamber, F, formed by the cross-partition V within the cistern and the removable cover E to the same, which cover is packed air-tight at its edges. The pipe G leads from the siphon of the closet to the minus pressure-chamber F, and it opens near the top of such chamber F, and the pipe H, leading from the flushing-rim of the closet, opens through the bottom of the cistern into the minus pressure-chamber F, and there is a valve-seat around the upper end of this pipe H and a 20 valve, I, that fits the same, and this valve I is upon the underside of the float K, and through this float K is the tubular valve-stem L, that is guided at the lower end by the parallel legs or guides N, that pass down within the pipe H. At the upper end of the tubular valve-stem L are openings 3, so that the water can overflow through the tube L, should it rise too 25 high in the cistern A. The stem 4 is fastened to the upper end of the tube L and passes freely through a hole in the top E of the minus pressure-chamber F, and there is a lever, S, pivoted upon the top E and acted upon by the closet-pull, and the stem 4 passes freely through an eye in this lever S, and there is a head to the stem 4, so that when the lever S is 30 acted upon the stem 4, tube L, float K, and valve I are lifted and the water rushes rapidly through the pipe H to the rim of the closet, and the descent of the water in the minus pressure-chamber and the suction action of the 35 descending water at the lower end of the tube

L cause a minus pressure in the chamber F sufficient to withdraw the air from the siphon of the closet by the tube G.

In cisterns of this general character which 55 I have heretofore constructed the hole in the cover E for the stem 4 has fitted said stem, to prevent the suction action in the minus chamber being interfered with by air passing in at this point. In my present improvement I 60 make this hole considerably larger than the stem 4, to allow air to pass freely through the same, and I place a valve, 6, at the upper end of the tube L and around the stem 4, said valve being preferably a short plug fitting 65 into the hole, with a conical top end to guide the same into the hole as the float carries the upper end of the stem L up against the under surface of the cover E, as seen in Fig. 3; but a disk of rubber upon the upper end of this 70 stem L may form the valve, as seen in Fig. 1. Hence in the normal position, with the valve I upon its seat, air can freely pass through the hole in the cover E, and the water is free to rise in the minus pressure-chamber F and 75 stand at the same level as it does in the cistern A; but as soon as the valve and float are lifted the valve 6 closes such opening in the cover air-tight, or nearly so. Hence the minus pressure-chamber F is rendered air-tight at this 80 point during the descent of the water in such chamber, and such water more fully exhausts the air from such chamber, insuring a perfect action of the siphon of the closet, and the valve 6 is kept closed by the action of the float K 85 until the water has descended sufficiently to allow the float K to descend, and at this moment the valve 6 is drawn away from the opening in the cover E, and air is admitted into the minus pressure-chamber F and to the siphon 90 of the closet, so that such siphon ceases to act; but the water continues to run out of the minus pressure-chamber F until the valve closes upon its seat, and in so doing sufficient water passes into the closet to properly fill and seal the trap 95 thereof.

It is preferable to make use of a small opening, 7, through the partition for the passage of the water, so that the water will not pass out of the cistern A as fast as it does from the minus chamber F, and only the contents of such chamber F will pass to the closet, together with 100

so much of the water in the cistern A as runs through this small opening 7 previous to the valve closing upon its seat.

I do not herein lay claim to a minus pressure-chamber, a flushing-pipe, a valve to close the same, and a float to sustain the valve until air is admitted into the minus pressure-chamber, as the same are set forth in my pending applications, Nos. 202,352 and 215,781, filed May 17, 1886, and October 9, 1886, respectively.

I claim as my invention—

1. The combination, in a water-closet cistern, of a minus pressure-chamber closed at the top and having a pipe, G, leading to the siphon of the closet, the flushing-pipe H, valve I, float K, tubular stem L, and the stem 4, passing through the top of the minus pressure-

chamber, and a valve, 6, at the top of the tube L, substantially as set forth. 20

2. The combination, in a water-closet cistern, of a minus pressure-chamber, a flushing-pipe passing therefrom to the closet, a suction-pipe leading to the siphon of the closet, a valve to the suction-pipe, and a float for sustaining the same when lifted, and a valve acted upon by the float to close an air-inlet opening into the minus pressure-chamber and to keep such valve closed until the float and valve commence to descend, substantially as set forth. 25 30

Signed by me this 12th day of October, A. D. 1887.

JOHN DEMAREST.
